UNITED STATES PATENT OFFICE

100,826

DESIGN FOR A COMBINATION COAT AND HOOD GARMENT

Edith Erd Marshall, Port Huron, Mich.

Application October 23, 1934, Serial No. 53,733

Term of patent 7 years

To all whom it may concern:

Be it known that I, Edith Erd Marshall, a citizen of the United States, residing in Port Huron, Michigan, have invented a new, original, and ornamental Design for a Combination Coat and Hood Garment, of which the following is a specification, reference being had to the accompanying drawing, forming part thereof, which shows in perspective the front of the garment.

The rear of the body of the combination garment is plain, while the rear of the hood is plain with the exception of the substantially parallel flounced collar which is joined to the hood by a seam, the invention residing essentially in the ornamental conformation of the forepart of the garment, as illustrated.

I claim:

The ornamental design for a combination coat and hood garment, substantially as shown and described.

EDITH ERD MARSHALL.
